UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

COUPLER POSITIONING DEVICE

Application filed December 5, 1929. Serial No. 411,820.

The device relates to means for automatically positioning the coupler of a railway car by gravity and has for its object to provide means tending to prevent a swingable coupler carrier from rubbing against adjacent parts of the car, which rubbing not only causes wear of the adjacent car part and/or the carrier but also restricts the free and easy swinging movement of the coupler carrier.

10 In the drawings:

Fig. 1 shows a typical application of my device to a railway car.

Fig. 2 is a section on line 2—2 of Fig. 1.

15 Fig. 3 is a perspective view of the carrier element.

Fig. 4 shows a supporting link in detail.

Fig. 5 shows a section through the preferred form of carrier.

20 Fig. 6 shows a section through a modified form of carrier.

Fig. 7 is a diagram showing the relation of the associated parts.

My improvement is shown in combination 25 with a form of coupler positioning device now in general use wherein the swingable coupler carrier 2 is suspended from the striking casting or other car part 3 by links 4 positioned at the opposite ends of the coupler 30 carrier, which links each have a double trunnion 5 at each end which engage journal bearings 8 and 9 in the carrier 2 and car part 3, respectively.

Such a swingable coupler carrier 2 usually 35 has substantial unrestricted movement longitudinally of itself, which movement, however, is limited by the side of the coupler coming in contact with the car part (at 6). The usual carrier is provided with lugs 7 to 40 retain the coupler substantially in the middle of the carrier.

It is desirable to restrict the swinging movement of the coupler carrier longitudinally of the car (laterally of the carrier) to 45 within narrow confines, which is usually accomplished by positioning the carrier between or adjacent certain parts 10—11 of the car.

The couplers 12 are usually positioned so 50 that when they are in draft (tension) they

are clear of the coupler carriers 2 (usually about $\frac{1}{8}$ "') so that as the train is running the coupler does not wear the carrier or vice versa. In other words, the end 13 of the coupler 12 attached to the draft gear is higher than the head of the coupler so that the portion 13 of the coupler which engages the carrier is obliquely positioned. Under buff (compression) and also when the coupler is not coupled with another coupler, the coupler rests entirely upon the outer edge of the present type of carrier which tips the carrier. This condition may also prevail on account of irregularities of construction and assemblage.

60 The present coupler carrier has a horizontal engaging surface upon which the coupler rests, but my invention is an improvement thereon and consists in making the engaging surface of the carrier for the coupler higher 65 adjacent the rear part 20, whereby the weight of the coupler is distributed over the entire width of the carrier, thus eliminating any tipping tendency; in fact, I prefer to form the engaging surface of the carrier somewhat 70 higher at the side thereof nearer the car so that the coupler would actually tip the lower part of the carrier away from the car.

75 The coupler 12 is higher adjacent the end 13 attached to the draft gear so that the 80 coupler rests entirely upon the outer edge of the horizontal engaging surface of the carrier, thus tipping the carrier, and forcing the lower part of the carrier against the adjacent car part. This tipping throws the 85 entire weight of the coupler on the outer lower trunnion of the supporting link, which causes excessive wear at that point or may result in bending the link. Fig. 7 shows my improved construction wherein the engaging surface 26 of the carrier for the coupler 90 is parallel to the bottom 13 of the coupler.

95 The contour of this engaging surface may be provided by forming an elevated portion 30 adjacent one side of the carrier, as shown in Fig. 6, but in order to increase the bearing area (wearing surface) between the coupler and the carrier, I prefer that the engaging surface 26 be parallel with and in contact with the coupler when the device is in normal 100.

position; or in other words, the engaging surface is in a flat plane, which plane is obliquely positioned relative to the plane of the swinging movement of the carrier and the links. (See Fig. 5.)

5 The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

15 1. In a railway car, the combination of a coupler carrier swingably suspended from the car to swing laterally thereof and provided with a coupler engaging surface, obliquely positioned relative to the plane of the swinging movement of the carrier.

20 2. A coupler carrier having a journal bearing and a coupler supporting surface positioned obliquely relative to each other.

25 3. In a railway car, the combination of a coupler carrier provided with a pair of journal bearings at each end thereof and having a coupler engaging surface therebetween, links swingably suspending said carrier from a car part, each of said links having a double 30 trunnion at its lower end engaging respectively said journal bearings, and a car coupler having the end attached to the draft gear, higher than the opposite end thereof whereby the portion of the coupler which engages 35 the carrier is obliquely positioned, said coupler engaging surface being obliquely positioned relative to a plane passing through the axes of said trunnions.

40 4. In a railway car, the combination of a coupler carrier swingably suspended from the car to swing in a substantially vertical plane and provided with a coupler engaging surface, a car part positioned adjacent one side of said carrier, and a car coupler having 45 a carrier engaging surface positioned in an oblique plane when assembled in the car, said coupler engaging surface of the carrier being substantially parallel to the carrier engaging surface of the coupler when in normal 50 position, whereby the carrier is held out of contact with said car part during the swinging movements of the carrier.

55 5. In a railway car, the combination of a coupler carrier swingably suspended from the car to swing in a substantially vertical plane and provided with a coupler engaging surface, a car part positioned adjacent one side of said carrier, and a car coupler having 60 a carrier engaging surface positioned in an oblique plane when assembled in the car, said coupler engaging surface of the carrier engaging said coupler at more than one line when in normal position whereby the carrier is held out of contact with said car part.

during the swinging movements of the carrier.

6. A coupler carrier having a journal bearing and a coupler supporting element journaled in said bearing having a supporting surface positioned obliquely relative to the axis of the bearing.
